UNITED STATES PATENT OFFICE.

JOHN BODENSTEINER, OF WALHALLA, NORTH DAKOTA.

TRACE-HOLDER.

1,119,231.

Specification of Letters Patent.

Patented Dec. 1, 1914.

Application filed August 20, 1913. Serial No. 785,767.

To all whom it may concern:

Be it known that I, JOHN BODENSTEINER, a citizen of the United States, residing at Walhalla, in the county of Pembina and State of North Dakota, have invented certain new and useful Improvements in Trace-Holders; and I do hereby declare the following to be a full, clear, and exact description of the invention, such as will enable others skilled in the art to which it appertains to make and use the same.

This invention relates to trace holders, and one of the principal objects thereof, is to provide means for holding the free ends of the traces of a set of harness when not in use.

Another object of my invention is to provide a trace holder which will be simple in construction, durable and efficient in operation, and inexpensive to manufacture.

A further object of my invention is to provide a connecting means for the back straps, the hip straps, and the crupper of a set of harness, said means also acting as a trace holder.

With these and other objects in view, the invention consists in the construction, combination and arrangement of parts herein-after more fully described and claimed and illustrated in the accompanying drawing, in which like reference characters indicate like parts throughout the several views, in which,

Figure 1, is a top plan view of my invention as secured in place on a set of harness, one end of a trace being shown attached to the holder. Fig. 2, is a transverse sectional view on the line 2-2 of Fig. 1. Fig. 3, represents a vertical transverse sectional view on the line 3-3 of Fig. 2. Fig. 4, represents a side elevational view of the spring.

Referring more particularly to the drawing, 5, indicates the back strap of a set of harness, 6, the hip straps, 7, the crupper, and 8, a trace. The holder is preferably formed in one piece, and comprises a substantially rectangular buckle providing parallel end bars 9, which connect a pair of rectangular members 10, to the lower bar 11, of one of which, the crupper 7, is attached, the back strap 5, being attached to the lower bar of the opposite member. The end bars 9, connect the members or frames 10, above the horizontal plane of the lower bars 11 thereof, and at the meeting points

of bars 9 and frames 10, are formed downwardly curved arms 12, which are connected by bars 13, said bars being offset below the horizontal plane of end bars 9, but lying in the horizontal plane of bars 11 of frames 10. Hip straps 6, are secured one to each of bars 13. Connecting bars 9, at their central portions, is a cross bar 14, which has formed thereon two pairs of spaced ears 15, said pairs being disposed on opposite sides of the central line of bar 14, and secured between each pair of ears, is one loop 16, of a bent leaf spring 17, said loops being secured in place by means of studs or rivets 18.

Formed on bars 9, and constituting a continuation of cross bar 14, are a pair of upwardly and inwardly curved hooks 19, said hooks having their upper ends bent outwardly as at 20. The ends of leaf spring 17, extend upwardly from ears 15, and have their upper ends curved inwardly as at 21, and normally bear against the upper end of hooks 19. It will be noted that spring 17, is made of a single strip of material, doubled upon itself at predetermined points to form the loops 16. The ends of the spring above the loops 16, are considerably wider than the remaining portion of the spring, so as to afford a broad bearing face against hooks 19.

When the harness is not in use, traces 8, may be attached to the holder by means of the eyes 22, commonly provided on traces, whereby the traces will be kept out of the dirt and in easily accessible position, and in a position which will not interfere with the placing of the harness on a horse. In attaching a trace to the holder, the eye will be inserted between the curved portion 20, of hook 19, and curved portion 21, of spring 17, and forced downwardly between said hook and spring. It will be understood that each of the traces of a set of harness, will be attached to one of the hooks, only one trace being shown attached however.

Although I have described the preferred embodiment of my invention, I may desire to make such changes in the construction, combination and arrangement of parts as do not depart from the spirit of the invention and the scope of the appended claim.

Having thus fully described my invention, what I claim as new and desire to secure by Letters-Patent is;

In a trace holder the combination with

a substantially rectangular buckle frame having downwardly directed ends, of a pair of transverse bars spaced therefrom to admit the hip straps of a set of harness therebetween, a longitudinal bar formed integrally on said transverse bars and centrally thereto, a pair of substantially S-shaped upstanding hook bars formed adjacent the extremities of said longitudinal bar and integral therewith, a pair of spaced socket ears formed centrally of said bar, a spring member including a body portion, integral loops formed on the ends thereto

and positioned in said socket ears and a pair of upstanding spring portions inwardly curved adjacent their extremities and contacting with said S-shaped bars, and means for securing said spring loops in said socket ears. 15

In testimony whereof I have signed my name to this specification in the presence of two subscribing witnesses.

JOHN BODENSTEINER.
